MILK BOTTLE FILLER ATTACHMENT

Charles O. Barger, Kent, Wash.

Application June 6, 1938, Serial No. 212,203

3 Claims. (Cl. 214—91)

This invention relates to bottle feeding attachments for filling machines and more particularly to a device of this character for feeding milk bottles into convenient handling position relative to the filling means.

The invention has for its principal object to provide an attachment for handling and feeding the bottles to be filled whereby to increase the speed of the filling operation with minimization 5 in manual labor incidental thereto and under improved sanitary conditions.

Other objects and advantages to be attained will more fully appear in the following description.

The invention consists in the general structure and in the particular parts and combinations and arrangements of parts thereof as hereinafter described and set forth in the appended claims, reference being had to the accompanying drawings 15 illustrating a practical adaptation of the invention, and in which

Figure 1 is a longitudinal vertical section, showing the tilttable table in position for initially receiving the crated bottles to be filled;

Figure 2 is a similar view showing the table with crated bottles thereon and moved to feeding position with relation to the filling machine;

Figure 3 is a top plan view with the tilttable table in position as shown in Figure 2;

Figure 4 is a fragmentary transverse sectional view through the tilttable table and adjacent portions of the supporting frame showing the pivotal mounting provision;

Figure 5 is a view partly in side elevation and partly in section, showing the tilttable table in rested position and the bottles as being fed therefrom, and also illustrating the circuit wiring and controlling provision for operating the motor of the device;

Figure 6 is a fragmentary section, on an enlarged scale, taken on or about the line 6—6 of Figure 5;

Figure 7 is a section on the line 7—7 of Figure 6;

Figure 8 is a sectional view similar to Figure 6 but taken on the line 8—8 of Figure 1; and

Figure 9 is a section on the line 9—9 of Figure 8.

Referring now to the drawings the numeral 50 10 designates the work table of any milk bottle filling machine, on which table the bottles are initially received, said table being merely illustrated conventionally in the drawings.

The attachment of the present invention comprises a stand including upright frames 11 at

its opposite sides which are connected by suitable cross members 12 some distance above the base or footing portions 13, the top portions of the side frame members 11 being connected by a shelf 14 which is flush with the bottle receiving table 10 of the filling machine when the attachment of the present invention is cooperatively positioned in working relation to the filling machine.

Pivots mounted on the supporting frame or stand is a tilttable table 15 comprising a generally flat plate portion attached at its opposite ends to triangular members 16, which latter are cross connected by a plate member 17 near their apex portions, said member 17 constituting a supporting shelf for an electric motor 18 the function of which will be later described. The table frame is further braced by the provision of a connecting plate 19 between the triangular members 16 and located adjacent the inclined edge portions of said members 16 at one side thereof.

The pivotal mounting of the table 15 is effected through the instrumentality of headed studs 20 constituting removable trunnions which are inserted through apertured bearing portions 21 provided at the top portions of the side frame members 11 and into aligned bores 22 provided therefor in the adjacent table frame and there securely fastened by set-screws 23. Due to the

location of the pivotal axis of the table frame close to the plane of the plate portion 15 of the table and the preponderance of the weight of the motor 18 and other parts carried by the triangular end members 16 and the weight being disposed at one side of the axis, there is an overbalancing effect which tends to move the table to the raised position in working relation to the bottle receiving table 10 of the filling machine, as shown in Figure 2, in which position of the tilttable table 15 projecting portions 24 at opposite corners of the table rest upon stop lugs 25' provided by cutting away the adjacent portions 14' of the shelf member 14 to expose the end portions of a cleat 25 secured on the underside of said shelf member 14, by which provision overtravel of the tilttable table is prevented when it swings to the raised position, and at the same time the table is free to swing in the opposite direction when force is applied manually thereto as will be later described.

The table plate portion 15 is provided at opposite sides with enlargements 26 of round cross section, said enlargements having longitudinal bores therethrough in which an opposed pair of shafts 27 and 28 are rotatably fitted, said shafts 55

having sprocket wheels 29 and 30, respectively, fixed thereon and located in cut-out portions 31 provided therefor in the table top 15, each pair of sprocket wheels 29 and 30 being connected by an endless chain 32, the upper stretches of said chain 32 being countersunk in transverse grooves 33 provided in the top side of the plate member 15. The air of endless chains 32 are cross-connected by a multiplicity of cleats 34 and constituting a conveyor for the milk bottles as will presently more fully appear, said cleats being relatively thin and beveled on their forward edge portions, as at 35, so as to ride under the bottles when held against movement thereabove, but being also of ample thickness to engage the bottles and move them along when not so held.

For driving the endless conveyor just above described, the motor 18 on the cross member 17 of the table frame is belted to the conveyor shaft 21, as at 36, and provision is preferably made to automatically start the motor when the tiltable table is moved to its raised position and to stop the motor when the table is moved from such position. For this purpose, as shown more or less conventionally in the drawings, the motor circuit includes an extension cord 37 which is plugged into the usual electrical outlet, said cord including one wire 38 leading directly to the motor and another wire 39 leading through an "on and off switch" 40 and thence through a wire 41 to the terminal element 42 of an automatic switch element 43, the opposite terminal 44 of which is connected by a wire 45 to the motor. The two terminal elements 42 and 44 of the automatic switch are conventionally shown as spring tongues and the element 42 is provided with an insulated button 46 which is normally projected through an opening 47 provided therefor in one of the stop lugs 25' the under side of the shelf member 14 of the table stand. The normal set of the resilient terminal elements 42 and 44 is such that the constant tendency is for them to move apart except when the adjacent projecting portion 24 of the table is brought to bear upon the button 46 of the element 42 as the table is moved into its raised position as shown in Figure 2, said elements 42 and 44 springing apart as the table is moved to its lowered portion as shown in Figure 1, in which position the bottles to be filled are initially applied to the table as will now be described.

In the tilted position of the table as shown in Figure 1, stop members 48, provided on the inclined edge portions of the triangular frame members 16 and having beveled end portions 49, engage the under side of the shelf member 14 of the stand, by which provision over travel of the table is prevented and the table held steady while the bottles are being applied to the table, 60 the bottles being contained in the open-work cases or crates 49 in which they have been cleansed and brought to the machine for filling.

It is here noted that the bottles are placed in inverted position in the crate for the cleansing operation, said crate having cage-like interior structure for holding the bottles in spaced relation to each other so that the external surfaces of the bottles as well as the interior surfaces are exposed to the action of the cleansing fluid.

To place the bottles upon the table 15 the latter is moved manually to the position shown in Figure 1 of the drawings and the crate containing the empty bottles is pressed against the table and supported against downward endwise movement by shoulder or cleat portion 50 ex-

tending lengthwise of one edge portion of the table, and while still pressing the case upon the table force is exerted to swing the table on its trunnions 20 to the closed position as shown in Figure 2. At this time the automatic switch button 46 is depressed by the engaging extension 24 of the table, thereby closing the circuit and starting the motor 18, and as soon as the crate 49 is lifted from about the bottles 51 the endless chain conveyor moves the bottles towards the receiving table 10 of the filling machine.

The bottles 51 continue to move as a group until arrested on the receiving table 10, whereupon the cleats 34 of the conveyor ride under the bottles remaining on the tiltable table 15.

As the preceding bottles become filled and are moved out of the way the following bottles are in turn moved off the table 15, and as soon as the last single bottle or transverse row thereof, as the case may be, is moved onto the shelf portion 14 of the attachment stand, which position is shown by dotted outline as at 51', in Figure 2, at which time the tiltable table 15 can be moved to the position shown in Figure 1 to receive another crate of bottles. It is thus seen that instead of an operator placing the respective bottles one or two at a time upon the receiving table 10 of the filling machine, a larger quantity is supplied to the table in quick succession and at a speed which is limited only by the filling capacity of the machine.

While it is not absolutely essential in the operation of an attachment of the character of that of the present invention, it is preferable to provide the tiltable table with upstanding guard flanges or rails 52 along its opposite side portions to prevent accidental displacement of the bottles laterally from the table during the travel of the bottles toward the receiving table 10 of the filling machine, and to have said guard flanges or rails 52 register in alignment with flared lugs 53 on the shelf portion 14, which latter guide the bottles onto the receiving table 10.

While the structure illustrated in the drawings embodies a practical adaptation of the present invention, it is obvious that considerable modification and alteration may be made and substituted without departing from the spirit of the invention as defined by the appended claims. The invention, therefore, is not limited to the specific construction and arrangement shown in the accompanying drawings.

What is claimed is:

1. A bottle feeding attachment for filling machines, comprising a tiltable table pivotally mounted in a plane whereby to be movable to a horizontal position in feeding relation to the bottle receiving table of the filling machine, and to a substantially vertical crate receiving position, said tiltable table being counterweighted with overbalancing effect whereby to be self-movable to horizontal position and normally sustaining a given load thereon in such position, a bottle feeding conveyor on said tiltable table, a motor for driving said conveyor, and means for automatically energizing said motor when the tiltable table is moved to horizontal position and for automatically de-energizing the motor when said tiltable table is moved to vertical position.

2. A bottle feeding attachment for filling machines, comprising a supporting stand, a transfer shelf on said stand in the plane of the bottle receiving table of the filling machine, a tiltable

table on said stand movable to a horizontal position in cooperative working relation to said transfer shelf and to a substantially vertical position to receive thereon a crate of bottles to be filled, 5 said tiltable table being counterweighted with overbalancing effect whereby to be self-movable to horizontal position and normally sustaining a given load thereon in such position, an endless conveyor the top flight of which is generally 10 substantially flush with the top face of said tiltable table but having transverse cleats projecting above and extending across the face of the table, said cleats having beveled leading edges 15 engaging the bottles on the tiltable table to move them normally from the tiltable table but moving under the bottles when the latter are arrested in their movement from the table, a motor on 20 said tiltable table for driving the endless conveyor, and means for automatically energizing said motor when the tiltable table is moved to its horizontal working position relative to the transfer shelf and for automatically de-energizing the motor when said table is moved from 25 its horizontal working position to its vertical crate-receiving position.

3. In a bottle feeding attachment for filling machines, a stand having a bottle transfer shelf arranged thereon to align with the bottle receiving table of the filling machine, a tiltable table comprising a body plate portion and a frame comprising triangular end members to which said plate portion is attached, said frame further including a shelf member connecting said triangular end members, the pivotal axis of said table being adjacent the plane of the body plate portion thereof, a crate supporting ledge on the outer side of said body plate portion, an endless conveyor on said tiltable table, the upper run of said conveyor being contiguous to the outer face of said body plate portion, a 15 motor mounted on said shelf member of the table frame, a driving connection between said motor and said conveyor, and stop means for arresting the tilting movement of said table in opposite directions, whereby to support the table 20 in horizontal working relation to the bottle transfer shelf and in a vertical crate receiving position away from said bottle transfer shelf.
